UNITED STATES PATENT OFFICE.

WILLIAM HUGHES MOUSER, OF JACKSONVILLE, FLORIDA.

DESIGN FOR AN ORANGE AND GRAPE-FRUIT PREPARER.

48,692.

Specification for Design.

Patented Mar. 7, 1916.

Application filed October 8, 1915. Serial No. 54,924. Term of patent 7 years.

To all whom it may concern:

Be it known that I, WILLIAM HUGHES MOUSER, a citizen of the United States, residing at Jacksonville, in the county of Duval and State of Florida, have invented a new, original, and ornamental Design for an Orange and Grape-Fruit Preparer, as shown in the accompanying drawing and described in the following specification.

This invention relates to a design for an instrument for preparing oranges, grapefruit, and the like, and has for an object to provide such an instrument of artistic design and appearance.

In the drawings: Figure 1 is a view of the device in top plan. Fig. 2 is a view of the device in edge elevation. Fig. 3 is a transverse sectional view showing the concavity of one portion of the device.

Copies of this patent may be obtained for five cents each, by addressing the "Commissioner of Patents, Washington, D. C."

The device comprises a handle portion 10 of oval or elliptical cross sectional formation, with a spoon-shaped member 11 at one end which is curved transversely as indicated more particularly at Fig. 3, and is also curved longitudinally as indicated at Fig. 2. At the opposite end two tines 12 diverge and are provided at their extremities with curved and pointed arrowhead-shaped points 13.

I claim:

The ornamental design for orange and grapefruit preparer as shown and described.

WILLIAM HUGHES MOUSER.
